TIMING MECHANISM

Raymond D. Smith, Pleasantville, N. Y.

Application July 26, 1927, Serial No. 208,549

24 Claims. (Cl. 161—1)

This invention relates to the provision of winding gear separate from time setting controls in the general type of timing mechanism disclosed in my co-pending application Serial No. 5 616,549, filed February 2, 1923 useful for effecting the hand controlled and time governed automatic action of an electric switch, gas valve, or any other kind of device whatever to which the present improvements may have application.

10 This invention further relates to the provision of drive gear in the class of mechanism above referred to whereby the time setting dial may be impellable by the running of the time movement so as to indicate the true time of day at all times 15 as well as the time of day at which the timer has been set to perform its automatic function.

Other objects and illustrative constructions will hereinafter be pointed out in greater detail, the following description having reference to the 20 accompanying drawings wherein:

Fig. 1 is a front outside view of the winding and time setting controls.

Fig. 2 is a view partly in section on the plane 2—2 looking in the direction of the arrows in 25 Fig. 1; there being shown only the timing mechanism and not the electric switch, gas valve or other useful agent to be controlled thereby.

Fig. 3 is a view taken in section on the plane 3—3 in Fig. 2 looking in the direction of the 30 arrows.

Fig. 4 is a fragmentary view looking in the direction of arrow 4 in Fig. 3.

Fig. 5 is a view taken in section on the plane 5—5 in Fig. 2 looking in the direction of the 35 arrows.

Fig. 6 is a view similar to Fig. 1 showing drive gear for the time dial.

Fig. 7 is an outside view looking at the right of Fig. 6 the casing being partially broken away 40 to show details of the time dial gearing partly in section on the plane 7—7 in Fig. 6.

Fig. 8 shows in enlarged detail a practical construction for the mounting of the time dial to be impelled with the running of the time movement.

Fig. 9 shows a modified form of time dial with the addition of drive gear to impel the time dial for indicating the correct time of day at all times as well as the times of day for which the pointers 50 are set to cause automatic actions.

Fig. 10 is a plan view looking downwardly on Fig. 9 the casing and certain details of the drive gear being shown in section on the plane 10—10 in Fig. 9.

55 Fig. 11 is a partial sectional view taken on the

plane 11—11 in Fig. 9 looking in the direction of the arrows and showing more clearly certain stops limiting the relative movement of spindle 17', combined gear and ratchet wheel rotor 37'—40', and manuals 39' and 47' to the purpose 60 of insuring that the power spring 25' shall be sufficiently energized to return the said manuals to zero position whenever displaced therefrom for effecting time settings.

As the present improvements are confined to 65 timing mechanism quite independent of the device to be timed thereby I have omitted the showing of any such device in the drawings but reference may be had to my U. S. Patent No. (Re-

issue) 15,044 granted Aug. 26, 1930 and to my co- 70 pending application Serial No. 616,549 filed Feb. 2, 1923 for examples of gas valves, electric

switches, and the like adapted for uni-directional or reciprocative, single or plural automatic actions timed by the rotation of cams or the like through 75 the instrumentality of pivoted members represented in the present disclosure by the front de-

tent 10 and the rear detent 11 which may or may 80 not have the common pivot 12 and which may co-

act in any desired manner respectively with the front cam 13 and rear cam 14 to control the ac- 85 tions of a device not shown under the separate and individual operative effect of said two cams respectively.

The present improvements are concerned with 85 the means for propelling and predetermining the time at which cam 13 shall act upon detent 10 and the selectively separate and different time at

which cam 14 shall act upon detent 11.

The system of rotative parts including cams 13 90 and 14 includes the main winding arbor 15 of any suitable time movement between the movement

plates 16 and 17 mounted in any suitable manner upon the frame plate 18 rigid with the front frame plate 19 and rear frame plate 20 which as a 95 whole are enclosed in a housing 21.

Main spring 25 of the movement may connect 100 at its inner end to winding arbor 15 and at its outer end to a frame post, not shown, in a manner to propel arbor 15 in a clockwise direction in Figs. 1, 3 and 5.

The power of spring 25 is held back by the action of any suitable retarding train in 105 mesh with the large gear 26 carrying the pawl 27 adapted to engage ratchet wheel 28 which ratchet

wheel in some movement constructions is fast to 105 the winding arbor 15, and in other movement constructions is given a frictional mounting upon arbor 15 through the axial acting thrust of spring 29 backed up by the adjustable nut 30 and acting

110 through the medium of a washer 31 to press

ratchet wheel 28 and the hub thereof against the shoulder 32 on arbor 15; the strength of this frictional mounting being such that main spring 25 cannot turn arbor 15 when ratchet wheel 28 is held from turning by pawl 27 on the retarding gear 26 but the strength of said frictional mounting is such that arbor 15 may be turned by crank 33 with sufficient force to overcome this frictional resistance. An example of this type of construction is old in the art as evidenced by U. S. patent to Gibney No. 1,150,514. I have shown crank 33 rigidly secured to the forward end of arbor 15 by providing a hole in said end of the arbor into which crank 33 may snugly fit and be retained by a set screw 34 projecting through a collar 35 and through arbor 15 to bear upon a spot in crank 33 and for which may be substituted of course, a tapered pin or any other preferably removable means of fastening. For instance, crank 33 may be threaded at its mounting end internally or externally to screw onto arbor 15.

Arbor 15 carries keyed thereto by a tongue on lock collar 36 the pinion 37 a cut out 24 in frame plate 18 accommodating same.

Between pinion 37 and collar 35 there is loosely pivoted on arbor 15 a hub 38 flattened at its forward end to carry in fixed rotative relation the time pointer 39 and carrying as an integral rotor fixedly mounted on its rear end the cam 14 flanked on its front face by the ratchet wheel 40 and on its rear face by the gear 41 all solidly assembled by rivets 42 or in any other suitable manner. Hub 38 and its carried parts as above described are rotated preferably, but not necessarily, in reduced speed ratio to pinion 37 through the idler or "back-gears" pivoted in unison by stud 43 upon movement plate 16 and comprising gear 44 in mesh with pinion 37 and gear 45 in mesh with gear 41.

Loosely rotatable on hub 38 between ratchet wheel 40 and time pointer 39 is a larger hub 46 given a bearing in the frame plate 19 and carrying at its flattened forward end in fixed rotative relation the time pointer 47 having the upstanding ear 48 and said hub 46 carries rigidly mounted at its rear end the trip dog 49 shown most plainly in Fig. 3.

Also loosely mounted upon hub 38 between hub 46 and ratchet wheel 40 is cam 13 having an opening 50 for the tongue 51 on trip dog 49 and having a circular opening 52 through which protrudes the end 53 of a spring pawl 54 mounted on gear 13 rigidly at 55 in such position that pawl 54 tends to seat itself in the teeth of ratchet wheel 40 whereby cam 13 is positively propelled in a clockwise direction in Fig. 3 so long as pawl 54 is permitted so to seat. The slight movement of tongue 51 in opening 50 permits pawl 54 to be lifted out of engagement with the ratchet teeth through the small increment of movement of trip dog 49 relative to cam 13 thus permitted, trip dog 49 being ineffective to disengage pawl 54 from ratchet wheel 40 unless purposely moved to the left in Fig. 3 or unless impeded in its clockwise travel as impelled by the rotation of cam 13 by the time movement because of the spring tension in pawl 54.

A time dial 56 is rotatably mounted by means of an eyelet 57 clamping said dial against the front face of the housing through the medium of a friction washer 58 which eyelet affords an opening for the rotatable parts hereinbefore described and may if desired be of such internal diameter as to afford a bearing for all these parts by proper fit with hub 46 either additional to the bearing

for said hub in frame plate 19 or in place thereof. Time dial 56 may be provided with a handle 59 for turning same for purposes hereinafter described.

The timing mechanism is provided with a stop lever 60 a tongue 61 of which engages with a tongue 62 on trip dog 49 at a position the exactness of which can be regulated by the set screw 63 locked by the nut 64.

In the normal position of parts which is that position to which the running of the time movement restores all parts after each setting and use of the mechanism, the two time pointers 39 and 47 are at top center position designated by broken lines in Fig. 1 and Fig. 2 corresponding to which cam 13 and trip dog 49 are positioned as shown in Fig. 3, stop lever 60 preventing the further clockwise rotation of trip dog 49 and therefore of pointer 47 the ear 48 of which prevents further clockwise rotation of pointer 39 and therefore of arbor 15 whereby the movement is prevented from further running down and all parts brought to rest. I do not limit myself to the particular means shown for stopping the running of the movement or to any means whatever as it will be plain the movement could be permitted to continue running until the power in spring 25 is entirely depleted.

To set the timing mechanism for action the crank 33 is first turned to the left or contra clockwise which, in the absence of anything to resist them rotates time pointers 39 and 47 also contra clockwise and away from their top center or zero position. In the position of the time dial indicated in Fig. 1 the pointers indicate the interval of time that will elapse before their individual return to zero position as impelled by the running of the movement and it is understood that cams 13 and 14 so co-act respectively with detents 10 and 11 that said detents are differently conditioned when said cams are at zero than when displaced therefrom whereby the automatic time controlled effect is produced upon the device, such as an electric switch or gas valve, to be timed.

Movement spring 25 has thus been energized and immediately starts in action retarded by the time train to rotate crank 33 clockwise at the same speed as arbor 15 and simultaneously rotates pointer 39 and pointer 47 in the same clockwise direction but at a different speed from arbor 15 owing to the gears 37, 41, 44 and 45. Upon the arrival of pointer 47 at top center position cam 13 acts upon detent 10 to effect the first time controlled action of the device to be timed. Thereafter pointer 47 ceases to rotate being arrested by stop lever 60 engaging trip dog 49 but all the other rotating parts continue to move under the power of spring 25 with the exception of cam 13 which as it continues to be propelled in clockwise direction in Fig. 3 through the engagement of ratchet wheel 40 with pawl 54 thrusts said pawl against the now stationary trip dog 49 and thereby upwardly and out of engagement with the ratchet tooth which has been propelling it whereupon the spring action of pawl 54 itself causes cam 13 to slip back until the pawl seats itself in the next following ratchet tooth and these short oscillations continue as each tooth of the ratchet wheel passes into and out of engagement with pawl 54 until finally pointer 39 arrives back at its top center position whereupon it is arrested by the ear 48 on pointer 47 which will act through the gears 37, 41, 44 and 45 to resist further rotation of 150

arbor 15 and crank 33 and bring the movement to a stop. The arrival of pointer 39 at its top center or zero position conditions cam 14 to act upon detent 11 so that the second time controlled actuation of the device to be timed takes place.

In the above description it will be understood that I do not limit myself to the cam 14 being driven through positive connection to gear 41 or to ratchet wheel 40, as cam 14 might as well be loosely rotatable relative to said ratchet wheel and gear and carry a pawl the equivalent of pawl 54 whereby cam 14 would be releasably driven by ratchet wheel 40 in the same manner that cam 13 is pictured and described as propelled, in which event the arresting of the movement of pointer 39 would not arrest the running of the time movement but only cam 14, and power spring 25 would then continue to run down until its power became depleted or until some other stop became effective as might be desired. Fig. 10 shows a mechanism wherein both time cams 13' and 14' are releasably impelled from what is in effect a common ratchet wheel 40', in which figure the winding of the movement spring 25' is designed to be done through gears 37' and 41' by mechanism the details of which may be understood in greater particular from reference to my co-pending application Serial No. 642,496 filed May 31, 1923 and in Fig. 10 it will be understood that a crank equivalent to crank 33 of Figs. 1 and 2 may be applied to rotate gear 37' and thence the winding arbor 15' which arrangement would differ from Figs. 1 and 2 in that the crank would be eccentric with relation to the time pointers. In Fig. 11 I have illustrated enough of the details of the construction disclosed in my last mentioned co-pending application to make clear its points of distinction from the corresponding mechanism shown in Fig. 2.

The time dial 56 in Figs. 1 and 2 is frictionally swivelled for purposes of setting the timer to act at predetermined times of day without direct reference to the intervals of time that are to elapse. For instance, if it be nine o'clock at the time of setting the timer to act upon detents 10 and 11, say at four o'clock and six o'clock, dial 56 is first turned so that figure nine is at top center position, pointer 47 is turned to figure four and pointer 39 is turned to the figure six which effects the entire time setting without computation of intervals of time in order to know what numbers on the dial the time pointers must be set against in order to act at four and six o'clock respectively. Since this is a common use of such a time indicating dial and since the initial positioning of the dial with the correct time of day at top center is an act that has to be performed at each setting of the timer I may serve the double purpose of rendering unnecessary this preliminary attention to the dial and make of same a sort of clock in that the correct time of day can at any time be told by observing the position of the dial in the following manner.

Figs. 6 and 7 similar to Figs. 1 and 2 respectively, show the dial 56' provided with gear teeth at its periphery in mesh with which is a pinion 65 fast to a spindle 66 having a bearing in frame plates 19' and 18' and having a thrust shoulder 67 against which a pinion 68 of same diameter as pinion 65 is thrust axially by a spring 69 acting between another shoulder 70 on spindle 66 and the slide collar 71. Pinion 68 is in mesh

with a large gear 72 of same diameter as the gear formed by toothing the edge of dial 65 and gear 72 may be mounted to turn rigidly with cam 14 so that dial 56' will be rotated in unison with cam 14 through the medium of the friction clutch represented in spring 69 and slide collar 71 permitting manual adjustment or correction of the setting of the dial by means of the handle 59'. Once adjusted with the correct time of day at top or opposite the zero mark 73 the rotating of the time dial will maintain the correct time of day at the top so long as the movement runs with properly geared, time keeping accuracy. I may accomplish the same result by making the digits or graduations stationary on the casing at the edge of the time dial which could thereupon carry a rotating marker that would always point to the correct time of day on such stationary graduations. In this connection see Figs. 24 to 27 inclusive of my co-pending application Serial No. 616,549.

In Fig. 8 I suggest a practical construction for mounting dial 56' geared for rotating as described. The eyelet 57 may be as in Fig. 2 and a shouldered collar 74 may be clamped by such eyelet rigidly against the housing 21, dial 56' being confined and loosely rotatable between eyelet 57 and the shoulder on collar 74.

Figs. 9 and 10 show a corresponding adaptation of drive gear for a time dial 56'' of the type disclosed in my co-pending application, Serial No. 642,496, which may have the gear 75 fixed to its rear face and driven from gear 41' by the pinion 76 friction held against collar 77 on spindle 78 by spring 79 deriving its thrust from a shoulder 80 on said spindle which latter carries at its forward end the pinion 81 in mesh with gear 75, the housing 21' being broken away at 82 to accommodate gear 75 and pinion 81, both or either of which could if desired be entirely inside of or outside of housing 21' to avoid the opening 82.

By reference to Fig. 11, which shows in clearer detail the construction of the mechanism including parts 13', 14', 15', 25', 37', 40', and 41', all of which together with parts 83 to 90 inclusive may be identical with the disclosure in my co-pending application Serial No. 642,496, it will be seen that although in the present improvements I have shown how a separate crank or other kind of winding manual may be introduced additional to time setting pointers 39', 47' and which as before said can as well be employed for turning winding gear 37' in Figs. 9 to 11 inclusive, for separate winding of the movement if desired, I do not thereby necessarily sacrifice the advantage which I believe to be new with these improvements, viz that pin 83 and flip stop 84 (see Fig. 11) prevent setting of the time pointers away from top center or zero position without first or simultaneously winding the movement spring 25' even though a separate manual be employed for such winding. And the permanent or zero stop 85 may still operate to establish a zero position or definite limit to which the spring 25' may run down, acting (as is shown for example only) through stop 86 on trip member 87, thus limiting the contra-clockwise travel of pointer 47' to its top center, or zero position, because of the fact that trip member 87 is fast to the same hub 88 with pointer 47. The up-standing handle, or ear 89, of pointer 47' correspondingly limits the contra-clockwise travel of pointer 39' to a corresponding position which, through the medium of the main

80

150

shaft 90 and of the before mentioned pin 83 and flip stop 84, limits the running down of spring 25' and insures that adequate winding of this spring shall accompany or precede any turning 5 of either pointer 39' or 47' in a clockwise direction away from zero position for the purpose of setting the time.

The idea of a constantly rotated dial to tell the time of day, irrespective of the settings and movement of associated pointers having to do with the device actuating function of the timing mechanism, is within the scope of this invention inclusive of timing mechanism which may be motivated not by a spring motor, but instead, by an 10 electrical motor, or by any other impelling power whatever that may be utilized to produce and measure time intervals. For instance, the form of timing mechanism shown in United States Patent No. 1,495,020 issued to Chester I. Hall, 15 may be geared to have its time dial impelled by running of a synchronous motor to avail of the various purposes and advantages of the present improvement.

It will also be clear that the expedients here 20 disclosed are applicable in the same or equivalent forms to the timing mechanism disclosed in my co-pending application Serial No. 183,838 in which connection, as in the case with pin 83 and flip stop 84 of Fig. 11 of the present disclosure, I may 25 remove the pin 82, or the flip stop 83, or both of the structure disclosed in said co-pending application so that the spring movement is free to run until its power is depleted, and I may apply 30 a wing handle or a crank for the purpose of crank 33, hereof, at any convenient point, such as at the forward end of gear 37' hereof, or of gear 56, of my said co-pending application, or to another gear meshing directly or indirectly with either of same, as a means of winding the movement.

It is pointed out that to retain pin 82 and the flip stop 83 (see Fig. 11, parts 83 and 84) of the structure of my said co-pending application, Serial No. 183,838, filed April 14, 1927, or members 45 equivalent thereto for preventing the running down or playing out of the movement spring to an indeterminate point out of definite correspondence to the zero position of the time setting pointers, insures that the time pointers shall never 50 be set for automatic operation in the mistaken idea that the movement spring is sufficiently wound to complete the automatic timing cycle when in reality it is depleted or run down beyond a state of operativeness.

55 In this important respect resides a very practical improvement over the many forms of timing mechanisms old in the art wherein the clock or time movement is commonly wound by a manual operatively separate from the time setting means and thereby requiring individual attention to the separate functions of time setting and of winding to be sure the movement is sufficiently wound to automatically complete the intended cycle of operations. The function of winding 60 cannot be accidentally neglected in my approved arrangement of separate winding means and time setting means which are operatively interconnected through the engagement of pin 83 and flip stop 84 before referred to.

70 Therefore, without intention of limiting this invention to any smaller scope than will cover all fair substitutes and equivalents as to uses, elements and combinations mentioned, what I claim is:—

75 1. In timing mechanism including a time move-

ment, in combination, a winding arbor for said movement, a timer rotatively impelled by said movement in co-axial relation to said arbor, but at a speed different therefrom.

2. In timing mechanism including a time movement, in combination, a winding arbor for said movement carrying a manual for turning same, and a timer rotatable by said movement at a speed different from said manual and carrying a time indicating pointer between said manual and said movement.

3. In combination, a spring driven time movement, a winding arbor therefor, a timer rotatable by said movement about a common axis with said arbor but at a different rate of speed from said arbor, and clutch means rendering said timer shiftable to selective rotative settings relative to said arbor.

4. In combination, a spring driven time movement, a winding arbor therefor, a timer rotatable by said movement about a common axis with said arbor but at a different rate of speed from said arbor, and clutch means rendering said timer shiftable to selective rotative settings relative to said arbor, together with a second timer rotatable by said movement also about said common axis, and clutch means rendering said second timer shiftable to selective rotative settings relative to said arbor and to the first said timer.

5. In combination, a spring driven time movement, a winding arbor therefor, a timer rotatable by said movement about a common axis with said arbor but at a different rate of speed from said arbor, and clutch means rendering said timer shiftable to selective rotative settings relative to said arbor, and a dial rotatable by said movement also about said common axis and cooperating with said timer to measure time.

6. In combination, a spring driven time movement, a winding arbor therefor, a timer rotatable by said movement about a common axis with said arbor but at a different rate of speed from said arbor, and clutch means rendering said timer shiftable to selective rotative settings relative to said arbor, and a dial rotatable by said movement also about said common axis and cooperating with said timer to measure time, together with separate clutch means rendering said dial shiftable to selective rotative settings relative to said timer.

7. In combination, a time movement, a timer rotatable to variable settings removed from a stop determined position of rest and returnable to said position by said movement, mechanism operated by said timer as it nears its said position of rest, a time indicating dial co-operating with said timer to measure time and rotatable by said movement about a common axis with said timer.

8. In a timing mechanism including a time movement designed to be manually energized to complete a selective cycle of automatic action, in combination with said movement, a winding manual connected to require a plurality of rotations for fully winding said movement, a settable indicator for determining said cycle of automatic action and connected to rotate a fewer number of times than said manual as impelled by said movement during the said cycle of automatic action, and means to insure that the setting of said indicator shall be accompanied or preceded by sufficient winding turns of said manual to so energize said movement that the latter will complete the cycle of automatic action represented by the setting of said indicator.

9. In timing mechanism in combination, a de-

- vice to be timed, a spring driven timing movement, a winding spindle connected to energize said movement, a time graduated dial rotatable about the axis of said winding spindle and connected to be impelled by said timing movement at a lower speed than said winding spindle during the running down of said movement. 80
10. In timing mechanism in combination, a time graduated dial, time setting indicators adjustable to different positions thereon, a time movement connected to impel said dial and indicators, a spindle for winding said movement concentric with said dial and extending to the rear thereof, and manual means for turning said 85 spindle in winding direction adapted to connect to the front end of said spindle and to be rotated in front of said dial for winding the movement.
11. Center wind mechanism for a time switch embodying in combination with a spring driven 90 time movement, a movement rotated timer cam, and a time graduated dial connected to be impelled by said movement and to slip relative to said cam, a winding spindle operatively connected to said movement at the rear of said dial, and 95 manual means to rotate said spindle in winding direction and supported in front of said dial to turn in concentric relation thereto.
12. Center wind mechanism for a time switch embodying in combination with a spring driven 100 time movement, a movement rotated cam for determining the time of action of said switch, and a time graduated dial connected to be impelled by said movement and to slip relative to said cam, a winding spindle connected at the rear of said dial to wind said movement, manual 105 means rotatable at the front of said dial in concentric relation thereto, and an operating connection between said spindle and said manual means extending through the center of said dial.
13. In an interval timing mechanism in combination, a time setting pointer, a time movement, a spindle whereby said movement impels said pointer, a time graduated dial supported to rotate about the axis of said spindle at the rear 110 of said pointer, separate means whereby said movement impels said dial, both said pointer and said dial being adjustable to selective relative and absolute positions independently of said movement. 115
14. In a double action interval timing mechanism in combination, two time setting pointers concentrically rotatable, a time movement to impel said pointers in unison, a time graduated dial supported to rotate about the same axis as said 120 pointers at the rear thereof, separate means whereby said movement impels said dial, stop means to limit the travel of said pointers but arranged to permit the uninterrupted travel of said dial, and means permitting said movement to continue its running thereby to continue the rotation of said dial when said pointers are stopped. 125
15. In a timing mechanism, in combination, a time setting pointer, a time movement, slippable 130 connections whereby said movement impels said pointer, a time graduated dial, supported to rotate about the same axis as said pointer at the rear thereof, separate connections whereby said movement impels said dial, and stop means arranged to limit the travel of said pointer but arranged to permit the uninterrupted travel of said dial as impelled by said movement when said pointer is stopped. 135
16. In a timing mechanism, in combination, a 140 time setting indicator, a time movement, slippable connections whereby said movement impels said indicator, a time graduated dial connected to be impelled by said movement, and means to limit the travel of said indicator without limiting the travel of said dial. 145
17. In a time-controlled device, timing mechanism, a manual means to wind the timing mechanism, a second manual means to pre-determine a time said mechanism shall cause an actuation of said device, a third manual means to pre-determine a later time said mechanism shall cause a subsequent actuation of said device, and connections whereby winding movement of the first said manual means must precede time setting movement of the other two said manual means. 150
18. In a timing mechanism in combination, a device to be timed, a spring driven timing movement including a winding spindle, a timer cam to pre-determine the time of action of said device and driven by positive connection to said spindle, a time graduated dial driven by slippable connection to said spindle, and manual means positively connected with said spindle for turning the latter to wind, and mounted to rotate concentrically with said dial. 155
19. In combination, a time movement, a manual means for winding said movement, and a time graduated dial connected to rotate about the same axis as said manual means, and a timer cam supported to rotate about the same axis 160 as said manual means and connected to be driven by said movement in positive relation to said manual means and in slippable relation to said dial.
20. In an interval timing mechanism in combination, a time setting pointer, a time movement, a spindle whereby said movement impels said pointer, a time graduated dial supported to rotate about the axis of said spindle at the rear of said pointer, separate means whereby said movement impels said dial, said pointer being adjustable to selective relative and absolute positions independently of said movement. 165
21. In an interval timing mechanism in combination, a time setting pointer, a time movement, a spindle with slippable connections whereby said movement impels said pointer, a time graduated dial supported to rotate about the axis of said spindle at the rear of said pointer, gearing comprising means separate from said spindle whereby said movement impels said dial, and a handle at the front of the timing mechanism for rotatively adjusting said pointer to selective relative and absolute positions independently of said movement as permitted by 170 the said slippable connections. 175
22. In an interval timing mechanism in combination, a time setting pointer, a time movement, a spindle with slippable connections whereby said movement impels said pointer, a time graduated dial supported to rotate about the axis of said spindle at the rear of said pointer, slippable gearing comprising means separate from said spindle and its said slippable connections whereby said movement impels said dial, both said pointer and said dial being adjustable through the yielding of said slippable connections and said slippable gearing respectively, to selective relative and absolute positions independently of said movement. 180
23. In an interval timing mechanism in combination, a time setting pointer, a time movement, a spindle with slippable connections whereby said movement impels said pointer, a time graduated dial supported to rotate about 185

the axis of said spindle at the rear of said pointer, slippable gearing comprising means separate from said spindle and its said slippable connections whereby said movement impels said 5 dial, a handle at the front of the timing mechanism for rotatively adjusting said pointer, and another handle for rotatively adjusting said dial, said pointer and dial being adjustable respectively by said handles to selective relative and 10 absolute positions independently of said movement as permitted by the said slippable connections and the said slippable gearing, respectively.

24. In an interval timing mechanism in combination, a time setting pointer, a time movement, a spindle with slippable connections whereby said movement impels said pointer, a

time graduated dial supported to rotate about the axis of said spindle at the rear of said pointer, slippable gearing comprising means separate from said spindle and its said slippable connections whereby said movement impels said dial, a handle at the front of the timing mechanism, gearing connecting said handle to said spindle for rotatively adjusting said pointer, and another handle for rotatively adjusting said dial, said pointer and dial being adjustable respectively by said handles to selective relative and absolute positions independently of said movement as permitted by the said slippable connections and the said slippable gearing, respectively.
